UNITED STATES PATENT OFFICE.

DANIEL M. REDMOND, OF PHILADELPHIA, PENNSYLVANIA.

MACHINE FOR MAKING PARAGON UMBRELLA-RIBS.

SPECIFICATION forming part of Letters Patent No. 364,436, dated June 7, 1887.

Application filed July 21, 1886. Serial No. 208,631. (No model.)

To all whom it may concern:

Be it known that I, DANIEL M. REDMOND, of Philadelphia, in the county of Philadelphia and State of Pennsylvania, have invented a new and improved method of and apparatus for strengthening, perforating, forming, tempering and testing paragon umbrella-ribs, of which the following is a full, clear and exact description.

10 In making the so-called "paragon" umbrella-ribs, the paragon wire, which is U-shaped in cross-section, is flattened at intervals while the wire is in an annealed or soft state, and perforated at the flattened portions 15 for the passage through the ribs of the pins or binding-wires by which they are connected to the top ring of the umbrella and to the umbrella-braces. After this the wire is hardened and tempered.

20 In order to counteract the weakening effect of flattening and piercing the ribs, it is found desirable to strengthen or re-enforce them at the flattened portions, so that the ribs may be of ample strength throughout to stand the 25 strain brought upon them in use. This strengthening or re-enforcing of the ribs is accomplished by inserting in the groove of the wire, at the points where it is to be flattened and perforated, short pieces of wire or strips of 30 metal previous to flattening and perforating; and the perforations are usually made through the re-enforcing strips, so that they not only strengthen and stiffen the ribs, but are themselves thereby securely held in place, and also 35 form bearings for the pins or binding-wires that unite the ribs to the top ring and the braces of the umbrella-frame.

Heretofore in the manufacture of these ribs the strengthening or re-enforcing pieces of 40 metal have been inserted by hand, and the ribs have always been formed in short lengths—lengths suitable for the umbrella-frame which they are to form. The perforating has been done by suitable punching machinery, in which 45 each short piece or rib is placed separately by hand and held while the piercing is performed. After punching the ribs they have been hardened by heating many of them together in a metal tube, and subsequently immersing them while hot in some cooling-liquid, usually oil. After this cooling in oil the ribs 50 have been tempered or annealed by mingling

them with numerous other heated wires, from which they take the required slow second heat by radiation. After this second heating and 55 after cleaning the ribs, which is a laborious and time-consuming operation, (rendered so by the burning of the adhering oil in the annealing process,) the ribs are severally tested by hand by taking each rib and bending it over 60 pins to the proper curve. If the ribs take the curve without breaking or cracking and when released spring back of their own accord to a straight line, they have been successfully treated; but, owing to the fact that the success 65 of this old method depends almost altogether upon the judgment and skill of the workman, many ribs fail to stand the test, and these ribs so failing are worthless and lost. Besides this loss, and the unavoidable loss of 70 time and labor incident to the many operations through which the ribs pass, and the cost of skilled labor required in carrying it on in anything like a practical manner, this old method is attended with another serious difficulty—viz., the warping of the short ribs in 75 the first tempering or hardening heat. This entails a separate operation of strengthening the ribs at the time of annealing, and the straightening is done by hand with the outlay 80 of considerable time and labor.

My invention consists, principally, of a method of manufacturing paragon umbrella-ribs, which consists, as practically conducted, in flattening, re-enforcing, perforating, tempering, annealing, and testing while the 85 grooved or paragon wire is in continuous lengths, thus conducting the work with mechanical precision, rapidly, and without skilled labor, and without many of the operations followed in the old method, and particularly avoiding loss in the tempering and testing operations.

The invention also consists of a machine, and its details, constructed for flattening, re-enforcing, and perforating the ribs in continuous lengths. This machine embodies guide-rollers for the paragon or grooved wire and feed-rollers and holding devices for the re-enforcing wire, a knife for cutting the short re-enforcing pieces from the re-enforcing wire, a reciprocating die and stationary anvil for flattening the wire, reciprocating punches and stationary punch plates and dies for perforat-

ing the wire, a reciprocating feeding device for drawing the paragon wire unremittingly through the machine, and a reciprocating knife and stationary anvil for nicking the wire 5 at regular intervals to facilitate the separating of the wire into lengths suitable for umbrella-frames.

Reference is to be had to the accompanying drawings, forming a part of this specification, 10 in which similar letters of reference indicate corresponding parts in all the figures.

Figure 1 is a plan view of my new machine for re-enforcing, flattening, perforating, and nicking the wire. Fig. 2 is a side elevation 15 of the same. Fig. 3, Sheet 2, is an enlarged transverse sectional elevation taken on the line $x-x$, Fig. 1. Fig. 4 is a similar view on line $x'-x'$, Fig. 1. Fig. 5, Sheet 3, is a similar view on the line $y-y$ of Fig. 1. Fig. 6 is a 20 similar view on $y'-y'$, Fig. 1. Fig. 7, Sheet 4, is an enlarged detailed longitudinal sectional elevation taken on the line $z-z$ of Fig. 3. Fig. 8 is an enlarged detailed sectional plan view on line $z'-z'$ of Fig. 7. Figs. 9 and 10, Sheet 4, 25 show, respectively, detailed top and edge views of the rollers and feed mechanism for the strengthening-wire, or wire from which the strengthening-pieces are cut. Fig. 11, Sheet 5, is a detailed plan view of the feed-motion 30 for feeding the rib-wire through the machine. Fig. 12 is a sectional elevation showing one of the punches and dies and one means for holding the rib-wire while being pierced, and Figs. 13 and 14 show, respectively, a side and plan 35 view of a modified device for holding the rib-wire while being punched. Fig. 15, Sheet 6, is a detailed plan view of the rear end of the machine, showing the reel for the rib-wire as it issues from the machine. Fig. 16 shows the 40 means employed for tempering and testing. Figs. 17 and 18 show, respectively, side and plan views of a portion of a completed umbrella-wire; and Fig. 19 shows the sectional **U** form of the paragon-wire, to which form it 45 is bent in long lengths before it enters the strengthening, flattening, and punching or piercing machine.

A represents the main shaft journaled in suitable bearings formed in or secured to the 50 main frame B, which is of appropriate size, form, and strength to carry all the operative parts of the machine.

Slow rotary motion is imparted to the shaft A from a suitable motor acting through the 55 drive-pulley C, its short shaft, and the cog-wheels C' C'; and the shaft A communicates reciprocating motion to the flattening-die D, Fig. 1, which acts against the stationary anvil D'. It also reciprocates the knife-stock d', 60 the two punches E F, which act against the stationary punch-dies E' F', respectively, and the nicking-die G, which acts against the stationary anvil G', all of which will be more particularly described below. The main shaft 65 A also communicates motion, through the medium of the two beveled gear-wheels H' H', to the short transverse shaft H, the office of

which is, first, to reciprocate the feeding device I for drawing the grooved paragon wire a, Figs. 17, 18, 19, Sheet 6, intermittently 70 through the machine, which it accomplishes by the crank-disk I' and connecting-rod I², and, secondly, to revolve the receiving-drum J, Figs. 15 and 16, Sheet 6, by means of an endless belt or chain, J', and sprocket-wheels J² J³, for winding upon the drum the wire a as it issues from the machine. The grooved wire a, as it enters the machine, is of wrought-iron and **U** shaped in cross section, as shown in Fig. 19, and it enters the machine in a continuous 80 length between the guide-rollers b b' at the front, and in being intermittently drawn through the machine by the sliding action of the feeding mechanism I it first receives at regular intervals the short re-enforcing wires 85 a', Fig. 18, then is flattened at intervals against the re-enforcing pieces a', as shown at a², then is twice perforated, as shown at a³ a³, Figs. 16 and 17, at the flattened and re-enforced portions, and finally is nicked between the perforations, as shown at a⁴, to enable the wire to 90 be easily separated into short pieces of the required length.

I prefer to use two sets of guide-rollers, b b', for leading the paragon wire to the machine; 95 but a single set might be used, if desired. The lower rollers, b, are peripherally grooved to receive the wire a, while the upper rollers, b', are made quite thin, to run in the gutter of the wire a, as shown clearly in Fig. 7, Sheet 4, 100 for forcing the wire a down into the grooves of the lower rollers, b, so that these rollers, while they act as guides to the wire, also act to straighten it and to remove from it any indentations or irregularities.

The upper rollers, b', are, by preference, made adjustable to and from the lower rollers, b, by the screws b², or otherwise, to enable the pressure of the upper rollers upon the wire in the grooves of the lower rollers to be regulated so 105 that more or less tension may be put upon the paragon wire. The upper rollers may be adjusted in various ways; but I prefer to use the screws b², which are swiveled at their lower ends in the uprights b³ and work in screw-threaded openings in lugs or projections formed at the upper ends of the plates b⁴. These plates carry the shaft-journals of the 110 rollers b' and embrace the edges of the uprights b³ by means of dovetailed flanges, as 115 shown clearly in Fig. 8, Sheet 4, so that by turning the screws b² by the cranks b⁵, or otherwise, the plates b⁴, and with them the wheels b', may be conveniently raised and lowered. Lateral guides b⁶ b⁶ for the wire a are placed 120 between the sets of rollers b b', as shown clearly 125 in Fig. 2; but these may be omitted, if desired.

In entering the long lengths of wire a to the machine, after one end is placed between the 130 rollers b b' it is pushed through the orifice c past the flattening-die D and its stationary anvil D' and past the knife-stock d', (see Figs. 1, 3, and 8,) thence past the two punches E E'

and F F' to the sliding feeding mechanism or device I, and is thence placed between the pivoted jaw *i* and stationary jaw *i'* of said feeding mechanism. It may be stated here that sliding motion imparted to the feeding device I by the crank-disk *I'* and connecting-rod *I²* automatically closes the jaw *i'* upon the wire *a* upon the back motion and releases the wire upon the forward motion, so that wire *a* is drawn intermittently through the machine, the wire resting at regular intervals.

The details of construction of the feed mechanism I will be more fully described below.

W represents a continuous wrought-iron wire from which the short re-enforcing pieces *a* are cut by the knife *d*, held in the knife-stock *d'*. The wire W is fed intermittently into the machine by the feed-rollers K K', which are geared together by the gear-wheels *k* *k'*, (shown in Fig. 10, Sheet 4,) and intermittently operated from the eccentrics *k'* on the main shaft A. This eccentric acts through the strap *k²* surrounding it, the links *k³ k⁴*, (see Fig. 9, Sheet 4,) rocking pawl-lever *k⁵*, and ratchet-wheel *k⁶*, the latter secured upon the shaft of the roller K. The pawl-lever *k⁵* is fulcrumed on said shaft, so that the pawl *k⁵* thereof engages with the teeth of the ratchet-wheel. The longitudinal movement of the connections *k³ k⁴*, caused by eccentric *k²*, rocks the pawl-lever *k⁵* and causes an intermittent rotary motion to be imparted to the feed-rollers K K', each movement being sufficient to feed the wire W the desired length for a single re-enforcing piece, *a'*.

In order to adapt the feed-rollers K K' to feed wires of different sizes I make the roller K' adjustable to and from the roller K by means of ordinary block-bearings and set-screws inserted in slots in the frame K², that receives the feed-rollers.

From the feed-rollers K K' the wire W is forced through an orifice, *c'*, made, by preference, in the main frame of the machine, which orifice is exactly in line with the orifice *c*, through which the paragon wire *a* passes, and also exactly in line with the knife and stock *d d'*, so that the down-thrust of the said knife and stock will sever the short re-enforcing pieces *a'* from the wire W and deposit them, as they are successively cut, into the groove of the paragon wire, as illustrated in Figs. 7 and 8, Sheet 4. The knife stock *d'* is held in a groove in a rigid vertical upright, *d³*, and is operated from the main shaft A by the cam *d²* and centrally-fulcrumed lever *d³*, which is connected with the stock at one end, preferably by means of a projection at the upper end of the stock, and acted upon at the other by the coiled spring *d⁶*, which holds the lever in contact with the cam, so that the revolution of the shaft and cam rocks the lever *d³* and vertically reciprocates the stock *d'*. The down-thrust of the stock *d'* causes the knife *d*, carried at its lower end, to sever a short re-enforcing piece, *a'*, from the wire W and de-

posit it in the groove of the paragon wire in front of the flattening-die D, between it and its stationary anvil D', as shown clearly in Fig. 8, Sheet 4. At this time the paragon wire *a* is at rest, and the flattening-die D is forced forward by the action of the eccentric *f* on the main shaft A, Fig. 3, Sheet 2, and compresses the wire *a* and re-enforcing piece *a'* between the die and anvil D', so that said wire and re-enforcing strip are made flat for a space equal to the width of the face of the die D. The grooved wire *a* is in this manner closed upon the re-enforcing wire, so that the latter is held securely in place, and it becomes in effect a part of the wire *a*. When the die D recedes, the knife and knife-stock *d d'* are elevated, and at this time the feeding mechanism I draws the paragon wire *a* along a stated distance, and the feed-rollers K K' feed the re-enforcing wire W forward the length of another re-enforcing piece, *a'*, ready for the next operation of the cutting-knife and flattening-die.

To insure the depositing of the short re-enforcing pieces *a'* in the groove of the paragon wire *a* as they are cut off by the knife, I locate the feed-rollers K K' so that the grooves thereof stand on a slightly-higher level than the orifice *c'*, and I slant the orifice *c'* slightly downward to give the wire W a downward pitch, as shown in Fig. 7, Sheet 4, so that as the wire W issues from the orifice its forward end will dip into the groove of the paragon wire. In addition to this I employ the plate *g* for depressing the forward end of the re-enforcing pieces into the paragon wire, as shown clearly in Fig. 7, Sheet 7.

For depressing the rear end of each re-enforcing piece I form the knife *d* with a projection or shoulder, *d'*, (see Fig. 7,) and cause the knife, after cutting off each re-enforcing piece, to be forced down into the paragon wire upon the re-enforcing wire. This down movement of the knife grips the re-enforcing wire in the paragon wire, and the cam *d²* is flattened at its outer surface, as shown at *d²*, Fig. 8, so the knife while gripping the re-enforcing wire will dwell a sufficient length of time for the flattening-die D to move forward and flatten the paragon wire upon the re-enforcing piece.

The plate *g*, Fig. 7, Sheet 4, is pivoted to another plate, *g'*, attached to the spring *g²*, which is attached to the rigid arm *g³*, so as to hold the plate *g* so that it runs in the groove of the paragon wire. The spring *g²* permits the plates *g g'* to have an upward movement, so that the flattened and re-enforced portions of the paragon wire may pass under the plate *g*, and the forward end of the said plate *g* is slightly beveled to form a lifting-cam to facilitate the passage of the flattened and re-enforced portion under the plate. The spring *g²* also causes the plate *g* to grasp the forward end of each re-enforcing piece *a* between it and the bottom of the paragon wire, so that while the knife *d* holds one end of each re-enforcing piece the other end is held by the plate

g at the time the wires are flattened by the die D.

The die D is connected to the eccentric f by the connecting-strap f', attached to the block f², to which the die proper is adjustably attached by the screw f³, as shown in Fig. 3, Sheet 2. The block f² slides in a suitable guide recess, f⁴, formed in the main frame of the machine, as shown in said figure, and the anvil D' is held in a recess, f⁵, made in the main frame, and the anvil is adapted to be adjusted by the screw f⁶ to adapt the die D to exert a greater or less pressure upon the paragon and re-enforcing wires. At the same time the die D is forced forward for flattening the paragon and re-enforcing wires the punches E F are forced forward by their respective eccentrics e h on the main shaft, for perforating or piercing the paragon and re-enforcing wires where flattened by the die D, thus forming the perforations a³ a³. (Shown in Fig. 17, Sheet 6.) The penetrating-points of the punches enter shallow recesses formed in the punch-dies E' F', and the wire is held in proper position against the faces of these punch-dies by a plate, F², (shown in Figs. 4 and 12,) which plate is perforated for the passage of the penetrating-points of the punches. The punches E F are duplicates of each other, each being connected to its eccentric by a connecting-strap, j, and each held in a way formed by dovetailed cleats j' j', secured to the main frame of the machine, as shown clearly in Figs. 4 and 12, Sheets 2 and 5.

In addition to the plates F², for holding the wire against the punch-dies, a pivoted button, o, (see Fig. 12, Sheet 5,) may be used, arranged to act upon the upper edge of the wire, to prevent it from lifting. In place of this button o a sliding bar, o', (see Figs. 13 and 14, Sheet 6,) may be used to prevent upward movement of the wire, and this bar is given a vertical reciprocating movement by means of a cam, o², on the main shaft A and a centrally-fulcrumed lever, o³. By this construction the wire is clamped by the bar o', and firmly held at the time the punches pass through them. At the time the punches E F and the flattening-die D are withdrawn from the wire by the action of their eccentrics on the main shaft A and the knife-stock d⁴ elevated, the feeding device I is carried backward by the action of the crank-disk I' and the connecting-rod I², so that it feeds the wire into the machine the required distance. Then the feeding device releases the wire, and is forced forward to grasp the wire again. During this forward movement of the feed mechanism the knife-stock d⁴ and knife d descend, and the flattening-die D and punches E F are forced forward, each to act upon the wires a a', as already described.

While various devices or mechanism for intermittently drawing or feeding the wire through the machine may be used, a feed mechanism having a reciprocating right-line action, so constructed that the reverse motion

of the connecting-rod will cause automatic grasping and releasing of the wire, is preferred. The feed-motion here shown consists, essentially, of the sliding block I³, that moves in a groove, I⁴, made in the main frame of the machine, (see Figs. 5 and 6, Sheet 3,) and the sliding block or flanged plate I⁵, that moves in another groove, I⁶. The connecting-rod I² is connected directly to the sliding block I³, and this block is connected to the block or plate I⁵ by the bar I⁷, the above-mentioned jaw i, (see Fig. 11, Sheet 5,) and the stop-button or link i², which is pivoted to the plate I⁵ and engages with the pin i⁵, secured in the jaw i. The jaw i is hook-shaped, fulcrumed at i⁶ to the plate I⁵, and is provided with an adjustable bit, i⁶, to act against the stationary jaw i' for grasping the wire a. The button i² is slotted at i⁷, in which slot the pin i⁵ works, and when in operation the pin i⁵ traverses this slot with each reciprocation of the bar I³. This gives the bar I³ a slight movement equal to the length of the slot i⁷ independent of the bar I³ before the jaw i acts to lock the bar I³ to the bar I⁵, and this independent movement is communicated directly to the jaw i for opening and closing it. Upon the backward movement of the whole feed-motion, the bar I³ and the said bar-jaw i move together independently of the bar of plate I⁵ until the pin i⁵ strikes the rear end of the slot i⁷. This movement is just sufficient to close the bits of the jaw i upon the wire. The bar I³ and the bar I⁵ will now be locked together by the closing of the jaw and the action of the plate-button i² and pin i⁵, so that the whole will be moved back together, drawing the wire along in the machine. Upon the forward movement the bar I³ will move independently of the bar I⁵ until the pin i⁵ strikes the forward end of the slot i⁷. This movement will open the jaw i and release the wire and lock the bars I³ I⁵ together, so that the whole will move forward for again grasping the wire and drawing it along in the machine.

The plate I⁵ is formed with a series of holes, m, for connection with the jaw i, and this plate is made adjustable by means of the screw m' and jam nuts m², so that by adjusting this plate the jaw i may be made to close more or less snugly upon the wire being treated, and in order to adjust the throw or distance of movement of the feed-motion the connecting-rod I² is made movable to and from the axis of the crank-disk I', preferably by means of the T-slot n made in the disk and the sliding T-plate n' placed therein, to which the wrist-pin is attached. The plate n' may be secured at any point in the slot n by a set-screw, n², so that the feeding of the wire will always be accurate. After the wire passes the feeding mechanism, having been re-enforced, flattened, and perforated, it passes between the nicking-jaws G and G', Fig. 6, the former of which is reciprocated at proper intervals for indenting or nicking the wire between the perforations a³ a³ to enable the wire to be easily separated into

strips of proper lengths. The jaw G is held in ways, as shown clearly in Fig. 6, Sheet 3, and is reciprocated from the main shaft A by means of the eccentric l, connecting-straps l', connecting-link l', and lever l", connected at its lower end to the link l', centrally fulcrumed in the arm l", and connected at its upper end to the jaw G.

From the nicking-jaws G G' the wire passes 10 to the receiving-drum J, (see Fig. 15, Sheet 6,) placed loosely on a square portion of the shaft J', which is slowly revolved by shaft H and the endless chain and sprocket-wheels.

The drum J, when filled with wire, is removed from the shaft J' and placed upon a support on shaft L, held by a post, L', in front of the hardening-furnace M, through which the wire is slowly but continuously drawn by the testing-drum P, and subjected in the furnace to a uniform hardening heat throughout its whole length. Next to and in line with the furnace M is placed the cooling-tank N, to which water or oil is supplied from the supply-tank N', and through which the wire is continuously drawn for suddenly and continuously cooling it as it issues from the furnace M. Next to the cooling-tank N and in line therewith is placed the annealing or tempering furnace O, through which the wire passes and 25 continuously receives its second or tempering heat. The drum P is revolved at a speed bearing a certain relation to the degree of heat maintained in the furnaces and to the size of the wire, so that the wire will receive just the required heat the required length of time, and no more or no less, and the drum P is of such size in circumference that the wire wound upon it is brought just to the proper curve for testing it.

40 The heat in the furnaces will be kept uniform and at just the required temperature while the wire is passing through them, so that every part of the wire throughout its whole length will be subjected to the same heat, and thus be uniformly tempered throughout, and the wire will be kept taut by the drums, so that the wire cannot warp either in the first or second heating.

Having thus described my invention, what 50 I claim as new, and desire to secure by Letters Patent, is—

1. The method herein described of treating paragon wire, which consists in re-enforcing, forming, and punching the same at intervals 55 in continuous lengths in a soft state, then passing the same in continuous lengths taut through a heating-furnace, cooling-tank, and annealing-furnace, and finally winding the same upon a testing-drum, substantially as described.

60 2. A machine for treating paragon wire, comprising mechanism for feeding the wire intermittently through the machine, flattening and punching dies, a feed for the re-enforcing wire, and a reciprocating knife for cutting the re-enforcing pieces, substantially as described.

65 3. The feed mechanism I, constructed to

draw the wire a intermittently through the machine, in combination with a feed, for the wire W and a reciprocating knife for cutting short lengths of wire from the wire W, substantially as described. 70

4. The combination, with the reciprocating knife for cutting the re-enforcing wire, of the reciprocating die for flattening the wire, substantially as described. 75

5. The combination, with the knife for cutting the re-enforcing pieces, of a flattening die and punches arranged to pierce the wire at the flattened and re-enforced points, substantially as described. 80

6. The frame of the machine formed with a passage, c, for the paragon wire, a passage, c', above the passage c for the re-enforcing wire, and feed mechanism for both wires, in combination with a reciprocating knife for cutting 85 short pieces from the re-enforcing wire, substantially as described.

7. The spring-supported holding-plate g, held to run in the paragon wire for holding the re-enforcing pieces on the paragon wire, 90 substantially as described.

8. The knife d, having the shoulder d', in combination with means for reciprocating the knife and forcing it down upon the end of the re-enforcing wire for holding it in the paragon 95 frame, substantially as described.

9. The knife d, formed with shoulder d', in combination with the spring-supported plate g, arranged to run in the paragon wire, substantially as described. 100

10. The reciprocating feed mechanism for the paragon wire, consisting of two sliding plates or bars, one carrying a stationary and also a pivoted jaw, the latter connected to another sliding plate or bar by a slotted connection to act through the pivoted jaw to lock the two sliding bars together, substantially as described. 105

11. The combination, with the disk I', connecting-rod I', and sliding bar I', of the opposite sliding bar, I", the stationary jaw i', and pivoted hook-shaped jaw i, pivoted to the bar I", and connected to the bar I' by a slotted plate, i", and pin i", substantially as described, 110

12. The combination, with the flattening and 115 punching dies, the knife for cutting the re-enforcing wire, and intermittent feed mechanism, of a nicking-die, G, consisting of a stationary and a reciprocating block, substantially as described. 120

13. The combination, with the flattening and 125 punching dies, a knife for cutting the re-enforcing wire, and mechanism for intermittently drawing the paragon wire through the machine, of the receiving-drum J, for receiving the paragon wire as it issues from the machine, substantially as described.
